(57) **CLAIM**

I claim the ornamental design for a top insert label holder, as shown and described.

DESCRIPTION

FIG. 1 is a perspective view of a label holder, taken from the front and right of the label holder;

FIG. 2 is a perspective view of the top insert label holder shown in FIG. 1, taken from the rear and left of the label holder;

FIG. 3 is a perspective view of the label holder shown in FIG. 1, taken from the front and left of the label holder;

FIG. 4 is a perspective view of the label holder shown in FIG. 1, taken from the rear and right of the label holder;

FIG. 5 is a top view of the label holder shown in FIG. 1;

FIG. 6 is a rear view of the label holder shown in FIG. 1; FIG. 7 is a bottom view of the label holder shown in FIG. 1;

FIG. 8 is a side view of the label holder shown in FIG. 1, taken from the right;

FIG. 9 is a side view of the label holder shown in FIG. 1, taken from the left;

FIG. 10 is a perspective view of an alternate embodiment of the top insert label holder shown in FIGS. 1-9, taken from the front and right of the label holder;

FIG. 11 is a perspective view of the label holder shown in FIG. 10, taken from the rear and left of the label holder;

FIG. 12 is a perspective view of the label holder shown in FIG. 10, taken from the front and left of the label holder;

FIG. 13 is a perspective view of the label holder shown in FIG. 10, taken from the rear and right of the label holder;

FIG. 14 is a top view of the label holder shown in FIG. 10; FIG. 15 is a rear view of the label holder shown in FIG. 10; FIG. 16 is a bottom view of the label holder shown in FIG. 10;

FIG. 17 is a side view of the label holder shown in FIG. 10, taken from the right; and,

FIG. 18 is a side view of the label holder shown in FIG. 10, taken from the left.
